UNITED STATES PATENT OFFICE.

ANDREW PURMAN RIGGS, OF SEATTLE, WASHINGTON.

HAIR-TONIC.

No. 923,999.

Specification of Letters Patent.

Patented June 8, 1909.

Application filed July 6, 1908. Serial No. 441,931.

To all whom it may concern:

Be it known that I, ANDREW PURMAN RIGGS, a citizen of the United States, residing at Seattle, in the county of King and State of Washington, have invented a new and useful Composition of Matter to be Used as a Hair-Tonic and to Cure Eczema and Dandruff.

My composition consists of the following ingredients measured in drams and in which is used,

Red coloring, (raspberry cake coloring) tincture of cudbear)	2 drams.
Oil mugget (oil of lilly of valley)	$\frac{1}{2}$ dram.
Copper sulfate	2 drams.
Potash nitrate	1 dram.
Table salt	1 dram.
Quinin	1 dram.
Alcohol, 150 proof	90 drams.
Water	30 $\frac{1}{2}$ drams.

Ingredients are readily mixed while cold and the tonic is applied in liquid form externally either to the head or to skin infections such as eczema and like diseases. The com-

position is preferably used, however, for curing dandruff and cleansing the scalp, thus restoring the natural growth of hair.

What I claim as my invention is:

1. A hair tonic and eczema cure comprising red coloring, oil mugget, copper sulfate, potash nitrate, table salt, quinin, alcohol, and water, substantially as described and for the purpose specified.

2. The herein described composition of matter for curing dandruff and cleansing the scalp, consisting of red coloring two drams, oil mugget one-half dram, copper sulfate two drams, potash nitrate one dram, table salt one dram, quinin one dram, alcohol 150 proof ninety drams, and water thirty and one-half drams, substantially as described.

In testimony whereof I have signed my name to this specification in the presence of two subscribing witnesses.

ANDREW PURMAN RIGGS.

Witnesses:

B. BROWN,
PAUL A. TALBOT.
